UNITED STATES PATENT OFFICE.

ROBERT H. BERKSTRESSER, OF YORK, PENNSYLVANIA.

BREAD-BOX.

1,241,330.

Specification of Letters Patent. Patented Sept. 25, 1917.

Application filed May 12, 1915, Serial No. 27,596. Renewed February 26, 1917. Serial No. 151,142.

To all whom it may concern:

Be it known that I, ROBERT H. BERKSTRESSER, a citizen of the United States, residing at York, in the county of York and State of Pennsylvania, have invented certain new and useful Improvements in Bread-Boxes, of which the following is a specification.

My invention relates to improvements in apparatus for holding bread-stuffs, protecting them from dust, dirt, or the like, and retaining the same suitably moist.

An important object of the invention is to provide apparatus of the above mentioned character, which is simple in construction, inexpensive to manufacture, and convenient in use.

Other objects and advantages of the invention will be apparent during the course 20 of the following description.

In the accompanying drawings forming a part of this specification and in which like numerals are employed to designate like parts throughout the same,

25 Figure 1 is a side elevation of apparatus embodying the invention,

Fig. 2 is a central vertical longitudinal section through the same, and,

30 Fig. 3 is a detail transverse section, taken on line 3—3 of Fig. 1.

In the drawings, wherein for the purpose of illustration is shown a preferred embodiment of my invention, the numeral 1 designates a preferably rectangular body portion 35 or shell, having a cover or lid 2 hinged thereto. This cover or lid is held closed by latch means 4, as shown. The shell 1 is supported by legs 5, as shown.

Arranged beneath the shell 1 and extending 40 transversely thereof is a guide casing 6, attached thereto, as shown at 7. The rear end of this guide casing 6 is closed, while its forward end is open.

45 Removably mounted in the transverse guide casing 6 is a drawer or tray 8, the upper side of which is open. The forward end of this drawer or tray has a head 9, extending outwardly therebeyond, as shown. This head is perforated centrally thereof as 50 shown at 10, to provide ventilation, and a vertically movable valve 11, is adapted to wholly or partly cover the perforations. This valve operates in guides 12, as shown. Disposed exteriorly of the bottom of the shell 1, and extending longitudinally thereof are conduits 13, attached to the bottom by

solder or the like. These conduits are preferably semi-cylindrical in cross-section, but this shape is by no means essential. At their outer ends these conduits 13 extend upwardly, in portions 15, disposed exteriorly of the ends of the shell 1 and attached thereto by solder or the like, as shown. The upper ends of the conduit portions 15 are closed, as shown at 17, and the inner ends 65 of the conduits 13 lead into the opposite sides of the guide casing 6, as shown.

The drawer or tray 8 is provided in its sides with openings or notches 18, adapted to register with the inner ends of the conduits 13, when the tray is in the closed position.

The shell 1 is provided in its bottom and ends with a row or rows of perforations 19, in communication with the exterior conduits 13. The bottom of the shell is provided with centrally arranged perforations 20, that communicate with the drawer or tray. The ends of the shell 1 are also perforated at 21, near and above the vertical 80 conduit portions 15 to permit of the escape of air from the interior of the shell.

In the use of the apparatus, a sponge or the like is saturated with water and arranged within the drawer or tray 8. The bread-stuff is arranged within the shell 1. The moisture from the sponge in the tray 8 passes through the apertures 20 directly into the interior of the shell 1 and also passes through the conduit portions 13 and 15 and apertures 19 and thereby indirectly into the interior of the shell. When it is desired to establish and maintain circulation of moisture-laden air through the interior of the shell 1, the valve 11 is raised to uncover 95 more or less of the perforations 10, whereupon atmospheric air will enter the draw 8 where it will take up moisture and from whence it will pass through the apertures 20, the conduit portions 13—15 and the apertures 19 into the interior of the shell 1. The air, moisture-laden or otherwise, is free to escape from the upper portion of the interior of the shell through the apertures 21, and from this it follows that circulation 100 of air through the interior of the shell may be readily established and maintained.

Under some conditions it is desirable to supply air, moisture-laden or not, to the central portion of the bottom of the shell 1 alone, as when it is desired to ventilate or 110 keep moist the lower portion only of a mass

of bread or cake. It will be noticed by reference to Fig. 3 that the same can be accomplished by merely drawing the drawer 8 outwardly to a certain extent, since then 5 the imperforate portions of the side walls of the drawer 8 will close the inner ends of the conduit portions 13 and bar communication between the same and the interior of the drawer 8, which atmospheric air will 10 be free to enter the drawer through the exposed portion of the top thereof, and can as freely pass from the drawer through the apertures 20 into the interior of the shell 1.

15 Having thus described the invention, I claim:—

An apparatus for the purpose described, comprising a shell having apertures in the upper portions of opposite upright walls 20 and lower apertures in said walls and also having central apertures in its bottom wall and other apertures in said bottom wall, between the central apertures and said opposite upright walls, a casing fixed below the 25 central portion of the bottom of said shell

and open at one end and having openings in its side walls, horizontal conduit-portions communicating with said openings and also communicating with the last-named apertures in the bottom wall of the shell, upright conduit portions communicating with the horizontal conduit portions and the lower apertures in said opposite upright walls of the shell and closed at their upper ends, a slideable drawer disposed in said casing and open at its upper side and having an opening in its outer end wall and also having openings in its side walls adapted to be moved into and out of registration with the inner ends of the horizontal conduit portions, and a valve carried by the drawer and arranged to control the opening in the outer end wall thereof. 30 35 40

In testimony whereof I affix my signature in presence of two witnesses.

ROBERT H. BERKSTRESSER.
